US0D1070910S

(12) **United States Design Patent** (10) **Patent No.:** **US D1,070,910 S**
(45) **Date of Patent:** **** Apr. 15, 2025**

(54) **COMPUTER DISPLAY SCREEN OR PORTION THEREOF WITH ICON**

(71) Applicant: **Eppendorf SE**, Hamburg (DE)

(72) Inventor: **Sarah Bracher**, Hamburg (DE)

(73) Assignee: **EPPENDORF SE**, Hamburg (DE)

(**) Term: **15 Years**

(21) Appl. No.: **35/520,415**

(22) Filed: **Feb. 1, 2024**

(80) **Hague Agreement Data**

Int. Filing Date: **Feb. 1, 2024**

Int. Reg. No.: **DM/235981**

Int. Reg. Date: **Feb. 1, 2024**

Int. Reg. Pub. Date: **Mar. 29, 2024**

(57) **CLAIM**

The ornamental design for a computer display screen or portion thereof with icon as shown and described.

DESCRIPTION

1. Computer display screen or portion thereof with icon
2. Computer display screen or portion thereof with icon

1.0 Front

2.0 Front

Figs. **1.0** and **2.0** are front views of a computer display screen or portion thereof with icon, showing the new design. The broken lines showing a portion of a computer display screen or portion thereof with icon forms no part of the claimed design.

1 Claim, 2 Drawing Sheets
